LINO SCUSA, OF PHOENIX, NEW YORK.

TOILET-PAPER WINDER.

1,421,730.

Specification of Letters Patent.

Patented July 4, 1922.

Application filed November 6, 1920. Serial No. 422,274.

To all whom it may concern:

Be it known that I, LINO SCUSA, a citizen of the United States, residing at Phoenix, in the county of Oswego and State of New York, have invented certain new and useful Improvements in Toilet-Paper Winders, of which the following is a specification.

This invention relates to machines for winding toilet paper and the like, and has particular relation to certain attachments for rendering parts of the machine automatic.

The object of the invention is to provide a machine of the class, which in addition to feeding, slitting and winding a plurality of toilet paper rolls, is equipped with means for automatically winding cores for said rolls, the forming of the cores being effected upon mandrels which later receive and wind the paper, and the winding of the cores upon one mandrel being simultaneous with the winding of the paper on another mandrel. A further object is to provide means for automatically affixing labels to the finished rolls of toilet paper before the latter are removed from the mandrels, the said labeling operation being effected simultaneously with the making of another series of the cores, and the winding of another series of the rolls. A further object is to provide novel and simple means for automatically and successively stripping the labelled rolls of paper from the mandrels. A further object is to provide novel, simple and automatic means for applying adhesives to both the core blanks and the labels. And a further object is to provide a novel automatic means for timing the successive operations and for indexing and holding the mandrels during the operative periods.

I attain these objects by the means set forth in the detailed description which follows, and as illustrated by the accompanying drawings, in which—

Figure 1 is a front end elevation of one form of toilet paper winder, to which my improvements are applied, the full and dotted lines indicating idle and operated positions, and certain parts being omitted for clearness. Fig. 2 is a front side elevation of the same. Fig. 3 is a vertical cross-section,

taken on line 3—3 of Fig. 2; showing the core and label pasting and feeding mechanisms; also showing the mandrel supporting reel and the indexing mechanism. Fig. 4 is an enlarged vertical cross-section, taken on line 4—4 of Fig. 2; showing the disposition and arrangement of the cams which operate parts of the core and label mechanisms. Fig. 5 is an enlarged diagrammatic view of the bevel gears which operate the stripping mechanism. Fig. 6 is an enlarged view of one of the mandrel driving-heads; showing the means for automatically connecting and disconnecting the mandrels. Fig. 6^a is a vertical section, taken on line a—a of Fig. 6. Fig. 7 is an enlarged detail view of the indexing lever in relation to the reel, taken on the line 7 in Fig. 2. Fig. 8 is a top-plan view, taken in the direction of the arrows of line 8—8 in Fig. 2. Fig. 9 is a vertical section, taken on line 9—9 of Fig. 8. Fig. 10 is a similar section, taken on line 10—10 of Fig. 8. Fig. 11 is a vertical longitudinal section, taken on line 11—11 of Fig. 8. Fig. 12 is an enlarged top-plan view of one of the clutch operating levers. And Fig. 13 is respectively a side and an edge view of one of the clutch members.

In the drawings, the main frame comprises chiefly the upright ends 2 and 2', which support all of the working and other parts. 3 represents the relatively broad web of paper, which is drawn through the machine by a grooved roller 4 and similar press-rolls 4' and 4^a. The roll 4 is mounted on the main driving shaft 4^b, which is fitted with a gear 4^c which meshes with gears 4^d and 4^e, which respectively drive the usual perforator 5, and a pair of slitter shafts 5' which are equipped with a plurality of rotary slitting knives, as 5^a and 5^b, which slit the web 3 into a number of narrow strips comprising the toilet paper x. The foregoing are all parts of an old and well-known device. My invention consists of the following parts:

6 represents a shaft whose reduced ends are journalled in brackets 6' mounted on the front side of the frame. Upon one end of shaft 6 is rigidly mounted a head having

three equally spaced arms 6^b, 6^c and 6^d, the free ends of which are perforated to rotatably receive the corresponding ends of mandrels 7, 7' and 7^a, upon which the cores, 5 the toilet paper, and the labels are successively wound, as the reel comprising the last named parts is rotated step-by-step, as indicated by the arrows in Fig. 3. On the opposite end of shaft 6 is mounted a sleeve 10 6^e, to which three corresponding arms 6^b, 6^c and 6^d are pivoted, so that they may be swung outwardly for releasing the corresponding ends of the mandrels while the rolls of paper α are being stripped from the 15 mandrels (see dotted lines in Fig. 2). These swinging arms are provided with suitable bearings for the ends of the mandrels, and said arms are provided with handles 6^f, by which the reel is rotated by the operator at 20 the completion of each winding operation. The mandrel 7 (see Figs. 1, 2, 3 and 6) is shown in the position for winding the paper, and when so positioned is rotated by a driving-head 8, which is mounted on the inner 25 end of a shaft 8', upon the outer end of which is mounted a pulley 8^a, the latter being driven by a pulley 4^f, mounted on shaft 4^b, by means of a belt 8^b. The driving-head 8 is provided with a number of eccentrically 30 disposed pins 8^c, which are spaced to receive flattened tongues 7^b of the mandrels, and which effect the rotation of the mandrels while permitting the latter to be moved into and out of the driving positions automatically 35 whenever the reel is rotated, as described. Similar heads 8 are provided for simultaneously driving the mandrels 7' and 7^a (see Fig. 6^a), while said mandrels are in the positions shown in Figs. 1, 2 and 3. 9 40 represents a bell-crank lever, which is pivoted to the end 2' of the frame, one arm 9' serving as a handle, while the other arm 9^a overlaps the pivoted arms of the reel, and is provided with an inverted V-notch 9^b, 45 which engages pins 9^c carried by said arms, for indexing and holding the mandrels 7 in their operative positions, as described. The lever 9 is resiliently held in the operated position by a spring 9^d, which permits the 50 lever 9 to yield, as shown by the dotted lines in Fig. 7, whenever the reel is forcibly rotated for freeing one of the pins 9^c, as well as for allowing the next pin 9^c to snap into the notch 9^b for indexing the corresponding mandrel for a subsequent winding of the paper α . 55 The toilet paper α is usually wound upon hollow cores 10, consisting of strips of cardboard 10', which are usually wound several turns and pasted or otherwise fastened, and 60 then telescopically applied to the mandrels which they preferably fit snugly. At the start of the winding, the free ends α' of the paper α are laid upon the cores 10 (see dotted broken lines in Fig. 2) before the 65 machine is started. The operator then grasps a handle 11' of a brush holder 11, which extends parallel to the mandrel 7, and swings the holder forwardly and downwardly (see dotted lines b in Figs. 1 and 3). The holder 11 is equipped with a number of brushes 11^a, 70 which when idle are submerged in a bath of water 11^b, and when the brushes are brought into contact with the light paper α , the latter becomes wet and adheres to the paste-board cores 10. This adhesion is sufficient to hold the paper α until the winding is well under way, after which there can be no slipping or yielding of the paper. When the rolls are completed, the machine is stopped and the brushes 11^a are again 75 brought into contact with the paper α (see dotted lines c in Figs. 1 and 3), which softens the latter sufficiently to cause it to break along the moistened line at the first slight turning of the reel, and at the same time 80 causes an adhesion of the ends of the paper, which lasts until the labels are finally affixed. 85

In the present case, the cores 10 are wound on the mandrels as they successively reach 90 the position held by the mandrel 7^a, while the labels are affixed to the toilet paper rolls α following the shifting of the mandrels to the position held by the mandrel 7' (see Figs. 1, 2 and 3). The mechanisms employed for 95 winding the cores and the labels, and for pasting these parts, as well as for stripping the labelled rolls from the mandrels, are operated intermittently, at the same or at different times, by a constantly driven shaft 12, 100 which is journaled in brackets 13 and 14. Shaft 12 supports a spur-gear 12', which is rigid on said shaft by a key 12^a, and said gear is driven by a smaller gear 12^b mounted on a shaft 12^c, upon which is a pulley 12^d, 105 the latter being driven by a belt 12^e. The opposite sides of the gear 12' are provided with a plurality of clutch sockets 12^f, which are engaged at suitably timed intervals by similar clutch members 15 and 15', the latter 110 being positioned adjacent and parallel to shaft 12, and a similar alining but independent shaft 12^x. Between the gear 12' and the bracket 13 are located and concentrically mounted on the shaft 12 the following parts: 115 A sleeve 15^a, which has a longitudinal slot 15^b, in which is slidably disposed the clutch member 15, the said sleeve having a circumferential groove 15^c in which a tooth 15^d of said member is disposed. Adjoining the 120 sleeve 15^a is a cam 16, having two throw-points 16' and 16^a which successively lift a horizontal lever 16^b by contact with a roller 16^c carried by said lever. The cam 16 moves with the sleeve 15^a. Next to the cam 16 is 125 another cam 17, having but one throw-point 17', which lifts a similar lever 17^a by means of a roller 17^b. Next to the cam 17 are two mutilated spur-gears 19 and 20. Both of said cams and the gears 19 and 20 operate 130

with the sleeve 15^a as one part. The levers 16^b and 17^a are pivotally mounted on a common shaft 17^c, which is supported by the brackets 13 and 14. The clutch members 15⁵ and 15' are normally under the tension of springs 15^e, which tend to force said members into engagement with the gear 12'. The clutch members are held in the released position shown in Fig. 11, which corresponds to 10 the full line position of the related parts in all of the views, by levers 21 and 21', each of which has a chisel-like free end which engages the teeth 15^a and forces wedge-like, the clutch members away from the gear 12'. 15 when the said members are rotated by said gear towards a certain point. The lever 21 is rigidly mounted on a shaft 21^a, one end of which is journalled in bracket 13, while its opposite end is supported by the bracket 14. 20 The shaft 21^a is rocked in the direction for lowering and releasing the free end of the lever 21 from clutch member 15 by another lever 21^b, also rigid on shaft 21^a, and whose free end is positioned in a recess 13^a in the 25 bracket 13, where it contacts with a three-point or star-gear 6^x carried by the reel shaft 6, the several points of the star-gear corresponding as to position with the arms 6^a, 6^c and 6^d of the reel. The arrangement 30 of the star-gear and the lever 21^b is such that, at the initial rotation of the reel, the levers 21 and 21^b are rocked downwardly for permitting the spring 15^e to move the clutch member 15 into engagement with 35 the gear 12', which effects the driving of the sleeve 15^a, the two cams, and the gears 19 and 20, as one part. By this construction and arrangement, every time the reel is shifted a step, as at the completion of the winding of 40 the rolls α , the clutch 15 operatively connects the cams and the gears 19 and 20, with the constantly rotating gear 12', for effecting their intermittent operations. 22 represents 45 through the machine and containing liquid glue, or other quick setting adhesive 22^x. 23 represents a similar trough which extends across the lower front of the machine. The trough 23 is supported by a rocking inclined 50 frame 23', whose lower end is pivoted to the corresponding feet 2^a of the main frame, and upon frame 23' is mounted a plurality of stacks of labels 23^a, there being one stack for each roll of the toilet paper α , as best 55 seen in Fig. 2. The full lines in Figs. 1 and 3 show the label holder in the released position, the dotted lines showing the operative position. Adjacent the trough 22 is positioned a shaft 22', which supports a number of paste 60 brushes 22^a, which normally lie submerged in the adhesive 22^x, ready to be swung clockwise by said shaft for applying the adhesive to the top ends of the labels 23^a. Adjacent the trough 23 is also positioned a rod 23^b, 65 to which is attached as many paste brushes 23^c as there are stacks of the labels 23^a. This rod is mounted on levers 23^d, which are pivoted at 23^e to the frame 23'. The rod 23^b is movable upwardly and inwardly for applying the adhesive obtained from the trough 70 23 to the bottom ends of the labels 23^a. 24 represents another frame, which supports a similar number of stacks of flexible cardboard strips 10', from which the cores 10 are made. The table 24 is mounted on a series of 75 rollers 24' disposed on an incline, as best seen in Figs. 1 and 3, so as to facilitate the free gravitation of the core blanks towards the right during the winding operations. The cores are wound upon the empty mandrels 7^a, during the interval in which the paper α and the labels 23^a are being wound 80 on the mandrels 7 and 7', and for this purpose each mandrel is provided with two or more longitudinal grooves 7^c, into which the 85 upper ends of the blanks 10' are forced at the proper time, by a series of friction rolls 25, which are mounted on a common shaft 25', the said shaft being fitted at one end with a ratchet wheel 25^a, which is rotated 90 by a pawl 25^b, the latter being carried and operated by a lever 25^c. 26 represents a shaft similar to 22', which supports a number of paste brushes 26', which normally lie submerged in the adhesive 22^x. The brushes 26' 95 are employed for applying the adhesive 22^x to the free ends of the core blanks 10', just before said ends are brought to a stop beneath a spring 26^a (see Fig. 3), which holds the said ends under compression until the adhesive takes effect. The dotted lines in Fig. 3 show the position of the free ends of the core blanks at the instant the adhesive is applied. The pasting and winding of the labels and the core blanks are accomplished by the 100 following means: 105

When the clutch member 15 is released and engages the gear 12', the sleeve 15^a, cams 16 and 17, and gears 19 and 20, all start rotating in the direction shown by the arrows in 110 Figs. 1, 9 and 10. The throw-point 17' of cam 17 from the start begins to lift the lever 17^a, from which depends a link 27, one of whose edges comprises a rack, which operates a pinion 27', which in turn is rigid on and rotates shaft 22', and swings the brushes 22^a (see dotted lines in Fig. 3) for applying the adhesive 22^x to the tops of the labels 23^a. Link 27 connects with one arm of a bell-crank 28, whose other arm connects by means 115 of a link 28' and a spring 28^a to one of the levers 23^d, which effects the rocking of the brushes 23^c for applying the adhesive to the lower ends of the labels 23^a. The horizontal arm of the crank 28 also connects through a 120 link 28^b to the lever 25^c, which rotates the friction rolls 25 and moves the core blanks 10' towards the mandrel 7^a. During the short interval required to operate the last 125 named parts, the gear 20 has also been ro- 130

tating in unison with the cams and other parts, but owing to the omission of a number of its teeth, as at 20', said gear is delayed in meshing with a gear 29, which is mounted on 5 a shaft 29'. The shaft 29' carries one of the driving heads, that connects with and rotates the mandrel 7', which contains the fully wound paper α and is about to receive the labels 23^a. So that by the time the adhesive is 10 applied to the opposite ends of the labels, the gears 20 and 29 become fully meshed and the winding of the labels starts. But just an instant before the gear 29 starts, the label supporting frame 23' is rocked from the full 15 line to the dotted line position (see Figs. 1 and 3) for bringing the pasted or gummed upper ends of the labels against the rolls α . This is accomplished by a link 16^d which depends from lever 16^b and resiliently connects 20 with a lever 23' by a spring 16^e. The lever 16^b in this instance is raised by the throw-point 16' of cam 16, which is timed to lift 25 said lever at the end of the pasting operations, and an instant before the gears 20 and 29 become meshed, as described. During the short interval required to wind the labels 23^a, the throw-point 16^a of cam 16 is moving 30 towards the lever 16^b, and just as the lower ends of the labels reach the rolls α , the point 16^a lifts lever 16^b and again rocks the frame 23' outwardly and presses the pasted free 35 ends of the labels tightly against the rolls α , which completes the label affixing operation. The cores 10 are wound in the same interval that the paper α and the labels 23^a are being wound. This is accomplished by the gear 19, which intermittently meshes with and drives a pinion 30, the latter being operatively connected with one of the driving- 40 heads 8 and operates the mandrel 7'. In order to allow the friction rolls 25 time to feed the paste-board blanks 10' into the slots of the mandrels, a few of the teeth of said gear adjacent the gear 30 are omitted. When 45 the gears 19 and 30 finally become meshed, the gear 19, owing to its greater diameter, rotates gear 30 several times during the winding of the cores 10. When the cores are nearly wound, the second lifting of the lever 50 16^b by the throw-point 16^a operates a link 26^b, a spring 26^c, and a lever 26^d, which is mounted on the shaft 26. This rocks the shaft 26 in the direction for applying the adhesive 22^x to the lower ends of the core blanks 10', as shown by dotted lines in Fig. 3. All of the last described operations are 55 preferably accomplished while shaft 12 and gear 12' are making one revolution, at the end of which the clutch member 15 is forced 60 outwardly against the tension of spring 15^e, by the chisel-end of lever 21, which engages the tooth 15^d. The lever 21 after being rocked by the star-gear 6^x is returned to the operative position immediately after the 65 clutch member has been released, by a spring

21^x, and is therefore ready to release the clutch 15 from gear 12' upon the completion of the several functions, as described.

A moment or two before the completion of the winding of the labels 23^a, certain parts 70 are made ready for stripping the finished and labelled rolls α from the mandrel 7'. This is accomplished in the following manner:

Sleeve 15^a is provided with a pin 31, which 75 rotates in the path of a lever 31', but does not engage said lever until sleeve 15^a has moved about three-quarters of a turn. Then the pin 31 engages an inverted V-tooth 31^a on the free end of lever 31' and depresses 80 said lever (see dotted lines in Fig. 10) for an instant, after which the said pin moves on clear of said lever. Lever 31' is rigid to a sleeve 31^b, which is journalled on shaft 21^a, and the lever 21' is also rigid to said sleeve, so that the depressing of lever 31' moves lever 21' away from clutch member 15', and allows spring 15^e to force said member into engagement with the opposite side of gear 12', which effects the rotation of a similar 85 sleeve 15^x, which supports the member 15'. Levers 21' and 31' are returned to and resiliently held in operative position by a 90 spring 31^x, which is connected to a pin 31^y carried by sleeve 31^b, and also to bracket 14. 95 The sleeve 15^x, which supports the member 15' is rigid on the shaft 12^x, on whose outer or free end is mounted a pulley 32, which drives through a belt 32' a similar pulley 33, mounted on the outer end of a shaft 33', 100 which is supported by the brackets 13 and 14. On the opposite end of shaft 33' is mounted a bevel gear 33^a, which drives a similar gear 33^b, the latter being mounted on a shaft 33^c which supports a sprocket 105 wheel 34. The stripping of the rolls α is effected by means of forks 34', which are carried by a chain 34^a, the said chain being supported at the opposite end of the machine by a similar sprocket 34^b. The chain 34^a is driven in the direction of the arrows 110 in Fig. 2. Following each of the forks 34' is a part 34^c which engages and travels along the underside of the mandrel 7' for supporting said mandrel while its left end is 115 freed from its bearings, for allowing the rolls α to be stripped off. The arrangement of the parts 34^c is such that, when the stripping is completed, one of said parts is left between the pivoted bearing 6^e of the reel and the first or adjacent roll of the paper α (see Fig. 2), and it remains in that position until the start of the next stripping operation. At the first movement of the chain 34^a, the part 34^c engages and forces the pivoted arm 120 6^c which supports the mandrel 7' outwardly, so as to provide clearance for the ejected rolls α , as shown by dotted lines in Fig. 2. 125

The provision of the reel, which carries the three mandrels, the latter adapted to be 130

successively moved one-third of the revolution of the reel, for positioning the mandrels for winding the cores; for winding a series of the rolls *x*, and for applying the labels 5 23^a to the finished rolls, when taken with the novel driving means provided for each mandrel, and the novel and accurate timing mechanisms for effecting the operations of the several parts automatically at the right 10 times, enables me to convert the toilet paper stock into finished rolls ready for packing and shipping at comparatively small expense, and besides, I am able to greatly increase and facilitate the production, there- 15 by effecting a great economy in the production, as well as requiring fewer machines and fewer operators for carrying out the work.

Having thus described my invention, what I claim, is—

20 1. In a toilet paper winder, the combination with the paper feeding and slitting parts, of a reel disposed in the path and rotatable in the direction of the travel of the paper, a plurality of mandrels journaled in said reel adapted to be successively moved towards the position for winding the slitted paper by the rotation of said reel, means for indexing said mandrels, means for driving the mandrels for winding the strips of paper, 25 30 means for winding hollow cores upon said mandrels before they are moved to the paper winding position, and means carried by said reel for effecting the starting of the core winding mechanism.

35 2. In a toilet paper winder, the combination with the paper feeding and slitting mechanism, of a reel, a plurality of mandrels supported by said reel adapted for winding the slitted paper as each mandrel is success- 40 45 sively brought to a certain position, means for indexing and holding the mandrels in said position during the winding operations, means for driving all of said mandrels simultaneously, means for affixing labels to the rolls of paper carried by one mandrel while the paper is being wound upon another mandrel, means carried by said reel for effecting the starting of the label winding mechanism, and means for stripping the 50 rolls from the mandrels at the end of the label affixing operations.

3. In a machine for winding toilet paper, the combination with the paper feeding and slitting parts, of a reel, a plurality of mandrels upon which the paper is successively wound supported by said reel, driving heads journaled in the frame of the machine for rotating said mandrels simultaneously, means for winding hollow cores on one man- 55 drel while toilet paper is being wound on another mandrel, means for winding labels on the finished rolls carried by one mandrel while the paper and cores are being wound at different points on said reel, means for 60 65 applying adhesives to the cores and the

labels, means for feeding the core blanks and the labels towards the winding positions, and means for stripping the rolls of labelled paper from said mandrels.

4. In a toilet paper winder, the combina- 70 tion with the paper feeding and slitting parts, of a reel disposed in the path and rotatable in the direction of the travel of the paper, a plurality of mandrels journaled in the reel adapted for successively winding the 75 slitted paper, means for winding hollow cores on said mandrels before they are moved into the paper winding position, means for affixing labels to the toilet paper rolls after their mandrels have been moved away from 80 the winding position, means for applying adhesives to the labels and core blanks, and means carried by the reel for effecting the starting of the parts which wind the labels and the cores and apply the adhesives. 85

5. In a toilet paper winder, the combina- 90 tion with the paper feeding and slitting parts, of a reel disposed in the path of the slitted paper, a plurality of mandrels rotatably supported by the reel, said reel being 95 operable step-by-step for successively bringing the mandrels into position wherein they may be simultaneously rotated, driving heads for operating the mandrels independ- 100 ently, means for indexing and holding the mandrels in axial alinement with the driving-heads, means for operating the mandrels in sequence for winding the slitted paper, means for affixing labels to the rolls of paper carried by one mandrel while the slitted 105 paper is being wound upon the next mandrel, means for winding hollow cores upon the third mandrel before it is advanced to the paper winding position, and means carried by the reel for effecting the starting of the label and core winding mechanisms.

6. In a machine for winding toilet paper, the combination with the paper feeding and slitting parts and means for driving the same, of a plurality of mandrels upon which 110 toilet paper is wound successively, driving-heads adapted to be successively engaged by the mandrels, a gravitational frame, adapted to support blanks for a plurality of cores, means for winding said blanks upon one 115 mandrel while toilet paper is being wound on another mandrel, a rockable frame adapted to support labels for a plurality of toilet paper rolls, means for applying an adhesive to the opposite ends of the labels, means for moving the label frame towards the finished rolls, means for rotating said rolls for wind- 120 ing the labels around them, means for moving the label frame towards the rolls for pressing the free ends of the labels against 125 the rolls, and means for stripping the labelled rolls from their mandrels.

7. In a toilet paper winder, the combina- 130 tion with the paper feeding and slitting parts, of a reel disposed across the path and

rotatable step-by-step in the direction of the travel of the slitted paper, mandrels journaled equidistantly around the reel, means for indexing the mandrels as they are 5 successively brought into the position for winding the paper, driving-heads for rotating the mandrels while the latter are held by the indexing means, means for winding cores upon the mandrels before they are 10 moved to the paper winding position, means for affixing labels to the rolls of paper after the mandrels are moved away from the paper winding position, a clutch mechanism controlling the core and label winding parts, 15 and means carried by said reel for releasing said clutch mechanism at the end of each paper winding operation.

8. In a toilet paper winder, the combination with the paper feeding and slitting parts, of a plurality of mandrels, a reel for supporting the mandrels adapted for successively moving the mandrels towards the position for winding the slitted paper, a driving-head for successively rotating each mandrel, means for indexing and holding the mandrels in operative engagement with the driving-heads, a gravitational frame supporting a supply of core blanks, a mechanism for feeding said blanks towards a mandrel, 25 means for winding the core blanks on said mandrel while the slitted paper is being wound on the preceding mandrel, a mechanism for applying an adhesive to the core blanks, a constantly rotating gear, a cam for 30 operating said mechanism, a clutch for operatively connecting said gear with said cam, and means carried by said reel for releasing said clutch for starting said cam and the core winding parts.

40 9. In a toilet paper winder, the combination with the paper feeding and slitting parts, of a reel disposed across the path of the slitted paper, a plurality of mandrels journaled in said reel adapted to be successively moved towards the position for winding said paper, means for winding hollow cores upon said mandrels before they are moved to the paper winding position, means for applying an adhesive to the core 45 blanks, a cam for effecting the operation of said adhesive applying means, a clutch for controlling said cam, and means set in motion by the rotation of said reel for operating said clutch.

55 10. In a toilet paper winder, the combination with the paper feeding and slitting parts, and a reel rotatable in the path of the slitted paper, of a plurality of mandrels supported by said reel adapted for winding 60 the slitted paper as each mandrel is successively brought to a certain position by the rotation of said reel, means for driving all of said mandrels simultaneously, means for affixing labels to the rolls of toilet paper 65 after they are moved away from the wind-

ing position, a cam for applying an adhesive to the opposite ends of the labels, a cam for pressing the opposite ends of the labels against the rolls of paper, a clutch controlling the operation of said cams, and means 70 for operating said clutch.

11. In a toilet paper winder, the combination with the paper feeding and slitting parts, of a plurality of mandrels adapted to be successively moved into the paper winding 75 position, a reel for supporting and shifting said mandrels, independent means for driving all of said mandrels simultaneously, a mechanism for winding cores on said mandrels in advance of the winding of the paper, 80 a mechanism for winding labels on the rolls of paper while other cores and rolls are being wound, and means for effecting the starting of both of said mechanisms by each step-by-step movement of said reel. 85

12. In a toilet paper winder, the combination with the paper winding and slitting parts, and a plurality of mandrels rotatably disposed in the path of the slitted paper, of a trough containing an aqueous liquid disposed adjacent the mandrels when the latter are in the paper winding position, a plurality of brushes normally submerged in the liquid, a brush-holder pivotally disposed parallel to said mandrels and adapted to be swung in the direction for bringing the wet brushes in contact with the ends of the slitted paper for effecting the temporary adhesion of the paper to the cores, and means for rotating the mandrels for winding the 100 paper. 95

13. The combination with the paper feeding and slitting parts and a reel disposed in the path of the paper, of a plurality of mandrels journaled in said reel and adapted to be successively moved towards the position for winding the slitted paper, means for winding hollow cores upon the mandrels before they are moved to the paper winding position, manually operable means for effecting the adhesion of the ends of the slitted paper to the cores prior to the starting of the machine, the operation of said means adapted to be repeated at the end of the paper winding operations for effecting the breaking of the slitted strips of paper and for effecting the adhesion of the broken ends of said strips to the bodies of the rolls, means for applying labels to the rolls of paper, and means for stripping the labelled 110 rolls from the mandrels without removing the latter from the reel. 115

14. The combination with the paper feeding and slitting parts of a toilet paper winder, of a reel disposed in the path of the paper, a plurality of mandrels carried by the reel adapted to be successively moved into the paper winding position, independent means for driving all of said mandrels, a mechanism for winding cores on the man- 125 130

dreis in advance of the winding of the paper thereon, a mechanism for winding labels on the rolls of paper while other cores and rolls are being wound, a clutch for operating both of said mechanisms, a mechanism for stripping the rolls of paper from the mandrels after the labels have been affixed, a constantly rotating gear, a clutch adapted

to connect the stripping mechanism with said gear, means carried by said reel for 10 effecting the starting of all of said mechanisms, and means for automatically releasing said clutches for stopping said mechanisms.

In testimony whereof I affix my signature. 15
LINO SCUSA.
